UNITED STATES PATENT OFFICE.

WILLIAM F. HELMOND AND FRANK A. COOK, OF HARTFORD, CONNECTICUT, ASSIGNORS TO UNDERWOOD TYPEWRITER COMPANY, OF NEW YORK, N. Y., A CORPORATION OF NEW JERSEY.

TYPE-WRITING MACHINE.

No. 831,951.

Specification of Letters Patent.

Patented Sept. 25, 1906.

Application filed January 3, 1906. Serial No. 294,424.

To all whom it may concern:

Be it known that we, WILLIAM F. HELMOND and FRANK A. COOK, citizens of the United States, residing in Hartford, in the county of Hartford and State of Connecticut, have invented certain new and useful Improvements in Type-Writing Machines, of which the following is a specification.

This invention relates to the ribbon-winding mechanism of type-writing and other machines; and its object is to provide efficient, simple, and inexpensive mechanism for automatically reversing the winding of the ribbon when either spool becomes empty.

To this end, arms are mounted in the path of the ribbon, one arm at each spool, said arms to be operated by the ribbon, as by means of knots or obstructions fixed upon the ribbon. When the ribbon is paid off from either spool, the obstruction upon that end of the ribbon engages the associated arm and vibrates the same, thereby putting a spring under tension, which spring is caused to press against a driving-shaft, thereby tending to shift the shaft into connection with the empty spool. A stop or a latch prevents the shifting of the shaft, however, until the spring gains sufficient tension, whereupon the continued movement of the ribbon-arm serves to release said stop or latch, and thereupon the driving-shaft is shifted by means of the tensioned spring, and a companion stop drops into place to prevent reverse shifting of the shaft.

The invention also includes improved means for enabling a reciprocating part of the machine to impart rotary movement to the driving-shaft.

In the accompanying drawings, Figure 1 is a front elevation of the improvements as applied to the well-known "Underwood" front-strike writing-machine, the parts being shown in full lines in normal positions. The left-hand spool is shown empty, and the dotted lines indicate the movements of the ribbon-arm, &c. Fig. 2 is a sectional front elevation illustrating details of means for rotating the ribbon-driving shaft. Fig. 3 shows details of the mechanism seen at Fig. 2. Fig. 4 is a plan, partly in section, of a part of the stop mechanism for controlling the shifting of the ribbon-driving shaft. Fig. 5 is a plan of one of the ribbon-spools and adjoining parts.

The ribbon 1 is wound upon spools 2 and 3 and threaded through an intermediate vibrator 4, the spools seated in cups 5 6 and mounted upon the tops of vertical winding-shafts 7 8. Upon the bottoms of the shafts are secured miter-gears 9 10, to mesh with miter-gears 11 12, the latter fixed upon a horizontal driving-shaft 13 in such a manner that by shifting the latter endwise one pair of gears may be disengaged and the other pair engaged. At Fig. 1 the gears 10 and 12 are shown in engagement, and the ribbon is wound upon the right-hand spool 3, the gears 9 and 11 being separated. The shaft 13 is rotated intermittently by means of a pinion 14, which is in mesh with a gear 15, fixed upon said shaft 13, the pinion 14 being rotated by a lever 16, which is caused to vibrate by means of a reciprocating member 17 of the type-writing machine. The winding and reversing mechanism is substantially the same for each spool, so that a description of one will serve for both.

The ribbon is threaded through a fork 18, provided upon the upper end of a vibrating arm 19. When the ribbon is nearly all paid off from the empty spool 2, an obstruction 20 upon the ribbon catches in said fork and vibrates the arm to the right and backwardly, as seen in dotted lines, the upper end of the arm being guided in a diagonal slot 21, formed in a fixed arm 22. At its lower end 23, the arm 19 is connected to a horizontal shaft 24, mounted in a bearing 24 and extending forwardly and rearwardly and having heads 25 26. When the arm 19 is rocked by the ribbon, the shaft 23 turns, and a spring or yielding finger 27, fixed upon the head 25, presses against a collar 28, which is fixed upon the shaft 13, thereby tending to shift the shaft to the left. This movement is temporarily restrained by a latch or stop 29; but the continued movement of the arm 19 not only increases the tension of the spring 27, but also swings up an arm 30 to engage a pin 31, fixed upon the stop 29, thereby lifting the latter and releasing the collar 28 and shaft 13, so that the spring 27 presses the latter endwise to the left, thus disengaging the gears 10 12 and reengaging the gears 9 11, so that subsequent rotation of the shaft 13 causes the spool-shaft 7 to wind and the direction of the ribbon to be reversed. Said

stop-releasing arm 30 is fixed upon the head 26 of the shaft 23. The arm 19 has at its lower end a hub which, by means of a diagonal screw or pivot, is swiveled upon the head 26 of the shaft 23, so as to permit the diagonal rearward movement of the arm 19 in the guiding-slot 21, the latter extending in the direction of the ribbon, as seen at Fig. 5. The arm 19 is returned to normal position by 10 a spring 34. When the ribbon is all paid off from the spool 3, a similar operation takes place, the spring 27 for this spool pressing against a collar 35 upon the shaft 13 and the shifting movement of the latter being temporarily restrained by a stop 36. The stops 29 and 36 are constantly pressed down by 15 light springs 37, which are fixed upon the bearing member 24.

Mounted loosely upon each of the spool-shafts 7 and 8, near its upper end, is a detent-arm 38, having a hub 39, in which is formed a recess 40, in which is placed a compression-spring 41 and ball 42. The spring presses the ball against the shaft, thereby producing 20 constant friction between the latter and the detent-arm or hub. By this means the arm is given a constant tendency to rotate in the same direction as the shaft. During the unwinding of the spool the detent-arm presses 25 against the ribbon-arm 19; but when the latter is thrown backwardly by the ribbon, as seen in dotted lines, it clears said detent-arm, and the latter thereupon rotates with the shaft 7 to the dotted-line position at Fig. 5, this movement being arrested by a fixed stop 33, the detent having a forked end 44, within 30 which said stop is placed. When the detent is in the operative position seen at Fig. 5, it locks the ribbon-arm 19, thereby preventing 35 premature return of the latter to normal position, which might occur, partly because of the reaction of its spring 27 and partly because of the pull of its returning-spring 34. Thus the detent locks the arm 19 in operative 40 position and assures the full benefit of the energy which has been stored up in the spring 27, which does the shifting of the driving-shaft 13. When the shaft 7 begins to wind, the detent 38, turning therewith, 45 returns to normal position, thereby releasing the ribbon-arm 19. The latter is returned to normal position by its spring 34. The detents 38 may, however, be omitted in some cases, and other variations may be resorted to. 50

55 The details of the devices for rotating the main driving-shaft 13 are shown at Figs. 2 and 3. The pinion 14 is fixed upon a barrel or head which is provided with ball-bearings. Said barrel comprises two parts, of which the 60 principal one is a screw 45, having next to its head a shoulder 46, upon which the lever 16 vibrates. The other part of said barrel consists of a collar 47, fitted upon a small shank portion of the screw. Said shoulder 46 is 65 formed with a cone 48, and said collar is

formed with a cone 49, and these coöperate with corresponding cones formed in the ends of a fixed bushing 50 to form races for two sets of balls 51, upon which the barrel turns. The end of the screw is threaded into the 70 pinion 14, whereby it is held against the collar 47 or an intervening washer 52. The lever 16 has a clutch to operate the pinion-barrel, said clutch consisting of a ball or roller, (shown in an inclined slot 54 in the hub of the 75 lever,) so as to run free when the lever is retracted, but to bite the shoulder 46 when the lever is advanced. The bushing 50 is fixed in a bracket 55, forming a part of the framework or casting of the machine and also having a bushing 56, in which one end of the shaft 13 is journaled. Secured to said bracket 55 is a fixed plate 57, having an eye 58, through which the collar 47 passes, and also having a ball 59 working in an inclined 80 slot 60 and serving as a back-check for the pinion-barrel. The driving-shaft 13 may, however, be otherwise rotated within the scope of our improvements.

Having thus described our invention, we 90 claim—

1. In a type-writing machine, the combination with a pair of ribbon-spools and an endwise-shiftable shaft for winding the spools, of a pair of stops, springs for setting 95 said stops, means upon the driving-shaft for coöperating with the stops in alternation to prevent endwise movement of the shaft, arms mounted in the path of the ribbon to be moved thereby, springs associated with said arms, means upon the driving-shaft to coöperate with the last-mentioned springs in alternation for shifting the shaft endwise, and means controlled by said arms for releasing 105 said stops when said shifting-springs have been put under tension.

2. In a type-writing machine, the combination with a pair of ribbon-spools and an endwise-shiftable shaft for winding the spools, of collars upon the driving-shaft, 110 movable spring-pressed stops mounted upon the framework in position to ride idly upon said collars, the latter so placed that by a movement in one direction one of said stops will engage its collar in a manner to lock the 115 shaft, and when the shaft is moved in the other direction the other stop will engage its collar so as to lock the shaft, a pair of arms movable in alternation by the ribbon, springs which are put under tension by the movements of said arms, for shifting the driving-shaft endwise, and means also called into operation by said arms in alternation after its spring is tensioned, for releasing the shaft 120 from the control of the stop so that the tensioned spring may shift the shaft endwise.

3. In a type-writing machine, the combination of a pair of ribbon-spool shafts, an endwise-shiftable driving-shaft, collars on said driving-shaft, stops or latches to engage 125

- said collars in alternation to prevent shifting of said driving-shaft, springs for said stops, vibrating arms projecting into the path of the ribbon and movable alternately thereby, 5 springs to engage said collars to press said driving-shaft endwise, arms connected to said ribbon-arms for releasing said stops, and springs to return said ribbon-arms to normal positions.
- 10 4. In a type-writing machine, the combination with a pair of ribbon-spool shafts and a shiftable driving-shaft, of stops for preventing shifting of the driving-shaft, springs for shifting said driving-shaft, arms operable by the ribbon for putting said springs under tension, a pair of normally idle detents, and means for enabling said detents to prevent premature return of said arms to normal positions and for releasing said detents.
- 15 5. In a type-writing machine, the combination with a pair of ribbon-spool shafts and a driving-shaft, of yielding means controlled by the ribbon for effecting disengagement between said driving-shaft and one of said spool-shafts and engagement between said driving-shaft and the other of said spool-shafts; and a detent mechanism having means for preventing return of said yielding means to normal position after disengagement from one spool-shaft and before engagement with the other spool-shaft.
- 20 6. In a type-writing machine, the combination with a pair of ribbon-spools and an endwise-shiftable shaft for winding the spools, of a pair of stops, springs for setting said stops, means upon the driving-shaft for coöperating with the stops in alternation to prevent endwise movement of the shaft, arms mounted in the path of the ribbon to be moved thereby, springs associated with said arms, means upon the driving-shaft to coöperate with the last-mentioned springs in alternation for shifting the shaft endwise, means upon said arms for releasing said stops when said shifting-springs have been put under tension, a pair of detents, and means for moving said detents into the path of said arms to prevent premature return of the latter to normal positions, and for releasing said arms 25 from the control of the detents when the ribbon begins to rewind upon the empty spool.
- 30 7. In a type-writing machine, the combination with a pair of ribbon-spool shafts, of a driving-shaft for said spools, arms movable in alternation by the ribbon, springs put under tension by the arms, for shifting said driving-shaft, stops or latches which prevent said springs from moving said driving-shaft, means controlled by said arms for releasing said stops, detents loosely mounted upon said spool-shafts and capable of rotation therewith, and friction devices tending to cause said detents to rotate with said shafts; said detents being kept in normal positions by
- 35 said arms, and being moved by said shafts 65 behind the arms as the latter are operated by the ribbon, and each arm being released from its said detent by the reverse movement of the latter caused by the opposite rotation of the spool-shaft when the ribbon begins to 70 wind upon the empty spool.
- 40 8. In a type-writing machine, the combination with a pair of ribbon-spool shafts, of a shiftable driving-shaft, a pair of stops effective in alternation to prevent endwise shifting 75 of said shaft, arms mounted in the path of the ribbon and movable thereby in alternation, stop-releasing arms connected to said ribbon-arms, yielding means for effecting endwise shifting of said driving-shaft, detents 80 mounted upon said spool shafts, each detent having a spring and a ball pressed by the spring against the shaft; each detent being turned by its shaft behind its arm when the latter is moved by the ribbon, and being also 85 restored to normal position by the reverse movement of the spool-shaft when the ribbon begins to wind upon its spool, and means for limiting reciprocation of said detents.
- 45 9. In a ribbon-spool-winding mechanism, 90 the combination with a driving-shaft shiftable endwise, of a gear upon said shaft, a pinion in mesh with said gear during the shifting movements of the latter, a shaft or barrel whereon said pinion is fixed, a reciprocating 95 lever loosely mounted upon said barrel and having an inclined slot and a ball therein for clutching said barrel, and a fixed support for said barrel, said support having an inclined slot and ball for preventing backward slip of 100 said barrel.
- 50 10. In a ribbon-spool-winding mechanism, 105 the combination with a driving-shaft, of a gear upon said shaft, a pinion in mesh with said gear, a screw threaded into said pinion, a cone placed upon said screw, a pinion-cone formed upon the head of said screw, coöperating fixed cones forming ball-races, balls in said races, a vibrating lever mounted upon the head of said screw and having a ball-clutch 110 for turning the same, and a ball-clutch between the screw and a fixed portion of the machine, for preventing backward rotation of the screw and pinion.
- 55 11. In a type-writing machine, the combination with a ribbon-spool and an endwise shiftable shaft for winding the spool, of a stop; a spring for setting said stop, means upon the driving-shaft for coöperating with the stop to prevent endwise movement of the shaft, an arm mounted in the path of the ribbon to be moved thereby, a spring associated with said arm, means upon the driving-shaft to coöperate with the last-mentioned spring 115 for shifting the shaft endwise, and means controlled by said arm for releasing said stop when said shifting-spring has been put under tension.
- 60 120 125

12. In a type-writing machine, the combination with a ribbon-spool shaft, and a shiftable driving-shaft, of a stop for preventing shifting of the driving-shaft, a spring for shifting said driving-shaft, an arm operable by the ribbon for putting said spring under tension, a normally idle detent, and means for enabling said detent to prevent premature return of said arm to normal position and for releasing said detent.
13. In a type-writing machine, the combination with a ribbon-spool and a shiftable shaft for winding the spool, of a stop, a spring for setting said stop, means upon the driving-shaft for coöoperating with the stop to prevent shifting of the shaft, an arm mounted in the path of the ribbon to be moved thereby, a spring associated with said arm, means upon the driving-shaft to coöperate with the last-mentioned spring for shifting the shaft endwise, means upon said arm for releasing said stop when said shifting-spring has been put under tension, a detent, and means for moving said detent into the path of said arm to prevent premature return of the latter to normal position, and for releasing said arm from the control of the detent when the ribbon begins to rewind.
14. The combination with a ribbon-spool shaft, of a driving-shaft, an arm movable by the ribbon, a spring put under tension by the arm, for shifting said driving-shaft, a stop or latch which prevents said spring from moving said driving-shaft, means controlled by said arm for releasing said stop, a detent loosely mounted upon said spool-shaft and capable of rotation therewith, and a friction device tending to cause said detent to rotate with said spool-shaft; said detent being kept in normal position by said arm, and being moved by said spool-shaft behind the arm as the latter is operated by the ribbon, and the arm being released from its said detent by the reverse movement of the latter caused by the opposite rotation of the spool-shaft when the ribbon begins to wind upon the spool.

WILLIAM F. HELMOND.
